ATTORNEY

UNITED STATES PATENT OFFICE.

LEOPOLD C. BRUCKER, OF NEW YORK, N. Y.

HOLDER FOR PHOTOGRAPHIC PLATES.

Application filed October 15, 1923. Serial No. 668,673.

To all whom it may concern:

Be it known that I, LEOPOLD C. BRUCKER, a citizen of the United States, residing at New York city, in the county of New York and State of New York, have invented new and useful Improvements in Holders for Photographic Plates, of which the following is a specification.

This invention relates to holders for photographic plates and has particular reference to a holder for the reception of a negative plate whereby the plate may be given its bath in a chemical solution, without requiring the hands to touch the solution during the developing process after the plate has been placed in the holder.

Another object of the invention is to provide a holder of the class mentioned wherein the negative plate may be rocked to cause the solution to pass back and forth over the plate during the developing process.

A still further object of the invention is to provide a holder for photographic plates which is simple in construction, cheap of manufacture and easy of operation.

With these and other objects in view, the invention resides in certain novel construction and combination and arrangement of parts, the essential features of which are hereinafter fully described, are particularly pointed out in the appended claims, and are illustrated in the accompanying drawing, in which:

Figure 1 is a perspective view of my invention per se.

Figure 2 is a longitudinal sectional view therethrough showing the manner of supporting a photographic plate.

Figure 3 is a transverse sectional view on the line 3—3 of Figure 2.

Figure 4 is a detail perspective view of a clamping device for use in the developing of photographic paper film.

In the process of developing the photographic plates or film, it has been the practice of passing the negatives through a chemical bath, which requires the hands of a person to grasp the plate and dip the same in the solution and at the same time impart to the plate a rocking movement so as to cause the solution to flow back and forth across the surface of the plate. This has been found very objectionable for the reason that the chemical solution stains the hands, and also causes finger print marks to show

on the plate after the same has been fully developed. My invention tends to overcome these objections as will be seen as the nature of the invention is better understood.

Referring more particularly to the drawing, the reference numeral 10 designates a frame which in the present instance is shown as rectangular in configuration, but which may be of any suitable shape and size to accommodate various plates. The frame 10 is preferably made of a relatively light metal and is provided with a pair of upstanding side flanges 11, 11 and an end flange 12. Only three sides of the frame are provided with flanges, which leaves one side open as 13 for the insertion of a photographic plate 14. The longitudinal flanges 11, 11 serve as a guide for sliding the plate in the open end 13 of the frame and the transverse flange acts as a stop for limiting the movement of insertion. The flanges 11, 11 are formed with lips 15 which prevent the plate 14 from lifting out of the frame. After the plate is inserted in the manner just described, the same is locked therein by means of a pivoted catch member 16 carried by the frame 10 at the open end 13 thereof. Secured to the underside of the frame are rockers 17 which extend the full length of the same in a longitudinal direction and which support the frame 10 above the bottom of the pan in which the frame is placed for the developing of the plate. In order to impart a rocking movement to the frame through the rockers 17, I provide handles 18 at the opposite ends of the frame which extend a suitable distance above the frame so that the hands of the operator may be positioned as far away as possible from contact with the solution to prevent the hands from becoming soiled.

From the foregoing description, it will be seen that the manner of inserting the plate 14 has been clearly set forth, and when inserted and locked, the holder is placed in the solution so as to permit the rockers to rest on the pan bottom after which a rocking movement is imparted to the frame to cause the solution to flow back and forth across the plate for such time as is necessary to bring out the exposure of the plate.

In Figure 4, I have shown a clamping member 20 consisting of identical U-shaped sections 21 pivoted together as at 22, and adapted for use in the developing of photo-

graphic cut film. The holder of the type mentioned is provided and receives a metal frame in the manner that it receives the photographic plate just described, after which the cut film is placed thereon and the member 20 applied so as to hold the film flat against the metal plate and in a locked condition as the sections 21 engage under the lips 15.

16 While I have described what I deem to be the most desirable embodiment of my invention, it is obvious that many of the details may be varied without in any way departing from the spirit of my invention, and I therefore do not limit myself to the exact details of construction herein set forth nor to anything less than the whole of my invention limited only by the appended claims.

17 What is claimed as new is:—

1. A holder for photographic plates comprising a frame, means for locking a photographic plate in said frame, and substitute rockers disposed beneath said frame.

2. A holder for photographic plates comprising a frame, means for locking a photo-

graphic plate in said frame, and rocking means disposed beneath said frame.

3. A holder for photographic plates comprising a frame having an opening therein for exposing both sides of the photographic plate, means on said frame for locking the plate therein, and rockers mounted beneath said frame and extending the length thereof.

4. A holder for photographic plates comprising a frame having an opening therein for exposing both sides of the photographic plate, means on said frame for locking the plate therein, and rockers mounted beneath said frame and extending the length thereof, and a handle formed at each end of said frame whereby a rocking movement may be imparted to said holders.

5. A holder for photographic plates comprising a frame, means for slidably receiving a photographic plate therein and for locking the same therewith, and rockers secured to and extending the length of said frame.

In testimony whereof I have affixed my signature.

LEOPOLD C. BRUCKER.

Certificate of Correction.

It is hereby certified that in Letters Patent No. 1,539,639, granted May 26, 1925, upon the application of Leopold C. Brucker, of New York, N. Y., for an improvement in "Holders for Photographic Plates," an error appears in the printed specification requiring correction as follows: Page 2, line 23, claim 1, strike out the word "substitute"; and that the said Letters Patent should be read with this correction therein that the same may conform to the record of the case in the Patent Office.

Signed and sealed this 7th day of July, A. D. 1925.

[SEAL.]

WM. A. KINNAN,
Acting Commissioner of Patents.
